WITNESS:

INVENTOR

BY *Victor J. Evans*

ATTORNEY

UNITED STATES PATENT OFFICE.

WILLIAM THOS. SHAW, OF PORTLAND, OREGON.

CONVERTIBLE SEAT.

Application filed May 24, 1924. Serial No. 715,702.

To all whom it may concern:

Be it known that I, WILLIAM T. SHAW, a citizen of the United States, residing at Portland, in the county of Multnomah and 5 State of Oregon, have invented new and useful Improvements in Convertible Seats, of which the following is a specification.

This invention relates to motor vehicles wherein the back of the front seat is 10 hingedly mounted to permit the back to be arranged in a horizontal position and in alignment with the front and back seats to form a bed, the invention having particular reference to a novel construction of means 15 for holding the back of the front seat in its normally elevated position, and permitting the said back to be quickly and conveniently released when its use is desired in the manner above stated.

20 The nature and advantages of the invention will be better understood when the following detailed description is read in connection with the accompanying drawing, the invention residing in the construction, combination and arrangement of parts as claimed.

In the drawing forming part of this application, like numerals of reference indicate similar parts in the several views, and 30 wherein:

Figure 1 is a fragmentary longitudinal sectional view through the body of the motor vehicle showing the back of the front seat in its lowered horizontal position, with 35 a part of the upholstering on one side of the body broken away to show the position of the holding means for said back when it is in its normally elevated position.

Figure 2 is a horizontal sectional view 40 through a portion of the vehicle body showing how the back seat is held in its vertical position by means of the invention.

Figure 3 is a fragmentary perspective view of the keeper attached to the said back.

Referring to the drawing in detail, A and B represent the front and back seats of the vehicle, while the back of the front seat is herein indicated at 10. This back is 50 hingedly supported as at 11 so that the back can be swung from its normal position to a horizontal position within the tonneau of the car, and supported in horizontal alignment with the front and back seats in the formation of a bed. Supported by the 55 foot board of the back seat is a bracket 12

upon which the back 10 reposes when swung to a horizontal position.

The present invention has particular reference to means for holding this back 10 in its normally vertical position, the means being so constructed that the back can be quickly and conveniently released to permit of its use in the manner above described, and also designed to automatically engage 65 the back and hold it in a vertical position when it is swung from a horizontal to a vertical position. This means is clearly illustrated in Figure 2 and consists of a bracket 13 adapted to be bolted or otherwise suitably secured to a part of the vehicle body at either side thereof. Pivoted on this bracket as at 14 is a locking lever 15 which is normally held in an active position by means of a coil spring 16 which is interposed between 70 the free end of the lever and that portion 17 of the vehicle body to which the bracket 13 is secured. This mechanism is wholly arranged within the upholstering of the car as shown in Figure 2, and is thereby wholly 75 concealed from view, with the exception of the working end 18 of the lever which is formed with a shoulder 19, and a curved surface 20, which slightly projects through an opening 21 formed in the upholstering 80 as shown. Arranged within the upholstering of the back 10 is what I term a keeper in the form of a curved bar 22, and one end of this bar projects beyond the edge of the back and is arranged to enter the opening 90 21 above referred to and passed between the lever 15 and the portion 17 of the car body. The keeper is curved to permit the working portion 23 thereof to lie parallel with the side of the car when the seat is swung to a 95 vertical position, the keeper being formed with a shoulder 24 to be engaged by the shoulder 19 on the lever 15 as will be readily understood. It will also be noted that the free extremity of the keeper is slightly bevelled as at 25 to allow this end to readily pass between the lever 15 and the portion 17 of the body when the seat is swung to its normal position, during which operation, the lever 15 and the keeper become automatically associated, and thus firmly hold the back of the seat elevated. When it is desired to lower the back for the purpose above mentioned, it is only necessary to strike the side 105 of the upholstering in which the lever 15 is arranged, in order to move the portion 18 of the lever away from the adjacent end of

the keeper, thus releasing the back of the seat so that it can be subsequently swung to a horizontal position. It might here be stated that the spring 16 is of sufficient strength to prevent the back of the seat from being released by casual jars or pressure against that side of the upholstering in which the lever is arranged, and that it requires considerable pressure or force in order to compress the spring 16 to effect the release of the back 10.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

Having thus described the invention, I claim:

A vehicle body including a seat having a hingedly mounted back, a bracket wholly arranged within the upholstering of the ve-

hicle body at one side of said body and immediately above the seat, said bracket including an offset terminal portion spaced from the side of the body, a horizontally disposed locking lever pivoted on said offset portion; a curved bar having its major portion arranged within the upholstery of said back, and having one extremity projecting from the side thereof and adapted to be received by the space between the side of the body and the offset portion of said bracket when the said back is swung to a vertical position, said extremity being designed to be engaged by the adjacent end of said lever, whereby the latter holds the back in a vertical position, resilient means for holding the lever in its active position, and said bracket being capable of longitudinal adjustment along said side upon which it is mounted, whereby said lever can be adjusted to compensate for lost motion or play of said back.

In testimony whereof I affix my signature.
WM. THOS. SHAW.
